(57) CLAIM

The ornamental design for shorts with front pocket, as shown and described.

DESCRIPTION

FIG. 1 is a top, front perspective view of shorts with front pocket;

FIG. 2 is a bottom, back perspective view thereof;

FIG. 3 is a front, top, inside-out perspective view thereof;

FIG. 4 is a front, bottom, inside-out perspective view thereof;

FIG. 5 is a front inside-out view thereof;

FIG. 6 is a front view thereof;

FIG. 7 is a back view thereof;

FIG. 8 is a right-side view thereof; and,

FIG. 9 is a left-side view thereof.

The dashed broken lines depict portions and features of the shorts with front pocket that form no part of the claimed design.

1 Claim, 9 Drawing Sheets
